NUMBERING MACHINE

Austin G. Riesenberger, Rockville Centre, N. Y.,
assignor to Wetter Numbering Machine Co.,
Brooklyn, N. Y., a corporation of New York

Application May 12, 1942, Serial No. 442,587

4 Claims. (Cl. 101—88)

The present invention relates to numbering machines and more particularly to improvements in the construction of the movable type block or drop cipher employed therewith and the bearing arrangement therefor. It is specially designed to produce a materially strengthened construction having greater bearing areas and more efficient distribution of the bearing surfaces. As a result, a more durable structure is obtained with substantial elimination of the tilting and displacement from the printing plane of the drop cipher as has been common to the devices of this type after long or extended use. This displacement resulting from wear has heretofore been the most prolific source of trouble for as will be appreciated to produce accurately aligned and uniform printing impressions requires firm and durable bearing support which will withstand the severe pressures to which these devices are subjected particularly as employed with high speed printing presses.

The improved features and advantages of the present invention will be more fully understood by reference to the accompanying drawing wherein like reference characters are applied to the corresponding parts in the several views.

In the drawing:

Fig. 1 is a plan view of a numbering machine to which the invention is applied.

Fig. 2 is a vertical, cross-sectional view thereof taken on line 2—2 of Fig. 1, having a portion of the ratchet broken away and showing the drop-cipher block supported in printing position.

Fig. 3 is a similar view showing the drop-cipher block in its depressed, non-printing position.

Fig. 4 is a view of the assembled number wheel, movable type block and ratchet as viewed from the side opposite that shown in Figs. 2 and 3.

Fig. 5 is a vertical, sectional view taken on line 5—5 of Fig. 4.

Fig. 6 is a plan view of the assembled parts shown in Fig. 4.

Fig. 7 is a view in side elevation of a portion of the numbers wheel showing the guideway slot formation, and

Fig. 8 is a view in perspective showing the movable type block formation.

The approved embodiment of the features of the present invention is here shown incorporated in a consecutive type numbering machine as commonly employed for automatic numbering and having a movable type block associated with each of the type or number wheels above the units wheel and adapted to be depressed below the plane of print as is usual in the machines of this

type. As shown, the machine comprises a suitable frame or bearing block 1 in which is supported the horizontal, stationary shaft 2. The number wheels 3 are mounted to rotate on the shaft 2 and are provided each with a ratchet wheel 5. The ratchet wheels are engaged by graduated pawls 6 carried by a swinging pawl frame 7. Oscillating movement is imparted to the latter through suitable connections from a spring supported vertically movable, actuating plunger 8 vertically movable in the frame 1. The usual spring pressed holding pawls are provided to engage the ratchet wheels of the several numbers wheels. The numbers wheels and actuating device in so far as referred to are of conventional and well known type and may be varied in form and arrangement to meet the specific requirements.

In accordance with the present invention, each 20 of the numbers wheels (with the exception of the units wheel as is customary) is formed to provide bearing for and to receive a movable type block or drop-cipher type block, commonly referred to as a drop-cipher, in an improved structural arrangement designed to contribute materially to the strength, firmness and security of support and resistance to wear or durability in maintaining proper printing alignment of the drop cipher as hereinbefore referred to. As 25 shown, the numbers wheels are formed with radially and angularly disposed guideway and bearing slots 12, the longitudinal axis of which is substantially tangent to the central bearing for the shaft 2. As best shown in Fig. 7, the slots 12, initially milled out, are machined through the wheel from one side to leave the connecting web or retaining bar 14, transversely spanning the slot at one side thereof and positioned intermediate of the shaft bearing and the perimeter of the wheel. Likewise, at the same side of the type wheel, left as shown in Fig. 5, an integral wall 15 is left in the milling operation, the upper surface of which is formed to provide a stop and bearing shoulder for the drop-cipher block when in retracted position. The underside of the shoulder 20' of the drop cipher block also engages bar 14 and acts similarly as a stop.

The drop-cipher block 16 of improved form is of general rhomboidal form having its parallel side walls 17—18 closely fitted to the guideway or slot 12 and having at one side thereof an elongated, transverse slot 20 freely to receive therein the retaining bar 14 of the wheel. The innermost end of the drop-cipher block is formed with a curved bearing portion 21 complementary in curva-

ture to the periphery of shaft 2 for bearing engagement therewith when in printing position as shown in Fig. 2.

The supporting shaft 2 is grooved or slotted, throughout its length as indicated at 22, one side wall 24 of the generally V-form slot being angularly disposed to co-operate with the foot of the movable block 16 as a cam to thrust the block 16 outwardly to printing plane upon rotation of the type wheel counter-clockwise as shown. The other side wall 25 of the slot 22 provides a shoulder to co-act with an inclined shoulder or detent 26 formed on the movable block 16 by forming of a groove 27 in the side thereof as shown. With the construction as described, the advance rotation of the type or numbers wheel, counter-clockwise from the printing position shown in Fig. 2 will upon registration of the shoulder 26 with the groove 22 permit depression of the movable block into inner or non-printing position and upon slight reverse or clockwise rotation, the retaining detent 26 is brought into the position of Fig. 3 wherein by engagement with the wall 26 the block is secured or locked against outward movement. It is thereby withheld from the printing plane until its carrying wheel is rotated in its sequence feed as is well understood.

In the improved construction shown, the drop-cipher block is assembled upon the numbers wheel from the ratchet side thereof, with the groove 20 receiving therein the connecting web or bar 14 and upon then securing of the ratchet 5 in position, the drop-cipher block is permanently retained in its operative position within the guideway slot 12 by its interlocked engagement with the integral web of the wheel. The ratchets 5 are, as shown, secured to the wheels 5 by tapered pins 30 having a force fit within the receiving apertures. The web 14, in addition to securing the movable type, also acts as a stop to determine the limit of movement of the block 16 by engagement with the upper and lower wall of the slot 20.

The improved bearing arrangement, it will be noted, provides for a maximum of bearing area engagement for the block 16 with the side walls 17 and 18; full width bearing at the foot of the drop-cipher block thus giving a maximum of bearing upon the shaft and lateral supporting engagement for the cipher block with the faces of the ratchets at opposite sides. In printing position the perimeter of the shaft 2 forces the drop-cipher block upward and locks it against the bottom of bar 14, eliminating any movement. The improved bearing arrangement accordingly more successfully meets the exacting requirements for a more durable and accurately supported drop-cipher block as is essential to good

printing operation. The strengthened bearing construction eliminates, to a substantial degree, the objectionable deformation of the movable type or displacement thereof such as to impair its printing accuracy or efficiency.

Having described my invention, I claim:

1. In a numbering machine, the combination of a slotted supporting shaft, a numbers-wheel mounted to be rotatable on the shaft and formed with an outwardly directed guideway slot formed at one side with a bar spanning the slot, a movable type block slidably fitted within said guideway slot and having an enlarged groove formed in one side thereof to receive said bar and formed with bearing portions engaging the guideway and the supporting shaft for the full thickness of the wheel and a ratchet secured to the wheel and effective to retain the movable type block in assembled position.
2. In a numbering machine, the combination of a slotted supporting shaft, a numbers-wheel mounted to rotate thereon and formed with an outwardly directed guideway slot formed at one side with a bar spanning the slot, a movable type block slidably fitted within said slot and having an enlarged groove formed in one side thereof to receive said bar and a ratchet secured to the numbers wheel at the side opposite from the bar and operative to retain the movable block in position.
3. In a machine of the character described, the combination of a slotted supporting shaft, a numbers-wheel mounted to rotate thereon and formed with an outwardly directed guideway slot formed at one side with an integral bar spanning the slot intermediate of the shaft bearing and the wheel periphery, a drop-cipher block slidably fitted in the guideway slot and having an enlarged groove in one side thereof to receive the bar and having parallel bearing portions engaging the guideway and an arcuate bearing portion to engage the shaft, said bearing portions being extended the full thickness of the wheel and a ratchet secured to the wheel and effective to retain the drop cipher block in assembled position.

4. In a drop cipher typographic numbering machine, the combination of a slotted shaft, a numbering wheel having a substantially radial cipher block receiving slot formed from one side and having on the other side a narrow, transverse bar between the shaft bearing and the wheel perimeter, a drop cipher block of the full thickness of the wheel and having on one side between the ends thereof a slot slidably to enclose said bar and a ratchet secured to the wheel and retaining the drop cipher block in assembled position.

AUSTIN G. RIESENBERGER.
